UNITED STATES PATENT OFFICE.

ALFRED SWENSEN, OF RIVERSIDE, ILLINOIS, ASSIGNOR TO THE CABLE COMPANY, OF CHICAGO, ILLINOIS, A CORPORATION OF ILLINOIS.

AUTOMATIC MUSICAL INSTRUMENT.

Original application filed May 12, 1916, Serial No. 97,153, now Patent No. 1,404,805. Divided and this application filed August 13, 1921. Serial No. 491,895.

My invention relates to automatic musical instruments and, more specifically, to instruments having motor-actuated air-tension-inducing devices; this application being a division of an earlier application filed by me on May 12, 1916, Serial No. 97,153, entitled "Automatic musical instrument" and patented January 31, 1922, No. 1,404,805.

10 Among the objects of my invention are those of providing an instrument of this type with improved means for controlling the air-tension-inducing motor, and for controlling the travel of the music-sheet.

15 Further objects will appear from the detailed description to follow, taken in connection with the appended claims.

In the drawings, in which one embodiment of my invention is shown—

20 Figure 1 is a front elevation of a player-piano embodying my invention, parts being broken away to show the interior construction;

25 Fig. 2 is a front elevation of the wind-chest, reservoir, feeders, and associated parts;

Fig. 3 is a plan view of the parts shown in Fig. 2;

Fig. 4 is a section, on the line 4—4 of 30 Fig. 3;

Fig. 5 is a section, on the line 5—5 of Fig. 4;

Fig. 6 is a bottom plan view of the key-bed and parts supported thereby;

35 Fig. 7 is a section, on the line 7—7 of Fig. 6;

Fig. 8 is a section, on the line 8—8 of Fig. 7;

Fig. 9 is a section, on the line 9—9 of 40 Fig. 10, showing the reroll stop;

Fig. 10 is a section, on the line 10—10 of Fig. 9; and

Fig. 11 is a front elevation of the tracker and music-sheet.

45 Referring now to the drawings in detail, the invention is shown in connection with a player-piano comprising a casing 10, any usual or suitable piano-action and pneumatic player-action, a selector-mechanism 11, which may be of any usual or suitable type, an air-motor 12 for causing the travel of the music-sheet, an expression-mechanism 13 for controlling the volume of tone, a motor-

operated air-tension-inducing device 14, and a foot-power air-tension-inducing device 15. 55 The selector-mechanism 11 comprises music-sheet winding and rewinding gearing, which is driven from the air-motor 12 by suitable driving connections 15a.

The motor-operated air-tension-inducing device comprises an air-pump 16, which may be of any suitable type, and an electric motor 17 for driving the air-pump. Current is supplied to the electric motor 17 through the leading-in wires 18 and 19. The motor 60 17 is controlled by means of a switch 20 in circuit with the leading-in wire 19. This switch 20 is operated by means of a stem 21 which is connected to a rod 22, the end of which is located in position to be engaged by the rod 23, which is connected to the lever 24, which is pivoted at 25 to the key-bed. The end of the lever 24 is turned upwardly to form a handle 26 which can be moved back and forth in the slot 27 of the key-bed. To start the motor 17, the handle 70 26 is moved to the extreme right to bring the rod 23 into engagement with the rod 22 and close the switch 20.

For stopping the motor 17, a pneumatic 80 28 is provided, having a forked arm 29 secured to its movable leaf. This forked arm is located in position to engage the down-turned end 30 of the rod 22. The pneumatic 28 is controlled by means of a valve-action 31, which is connected with the opening 32 in the tracker 33 by means of the conduit 34. The valve-action 31 is connected with the pneumatic 28 by means of the conduit 35, and with the air-pump 16 by 85 means of the conduit 36, the junction-block 37 and the conduits 38 and 39. The pneumatic 28 is provided with a spring 40 which normally keeps the pneumatic expanded and holds the forked arm 29 out of operative or 90 interfering engagement with the down-turned end 30 of the rod. 95

In addition to the sheet-controlled means, just described, for stopping the motor 17, a timed cut-out for the motor is provided, 100 comprising a rod 41 pivoted to the lever 24 and having a down-turned portion 42 for engagement with a push-button or cam-member 43 secured on the rod 44, a valve 45 located in position to be operated by the 105 rod 44, a conduit 46 controlled by the valve

45, a valve-action 47 connected with the conduit 46 and controlling the slow-acting pneumatic 48, a restricted conduit 49 connecting the valve-action 47 and the slow-
 5 acting pneumatic 48, a spring-valve 50 located in position to be engaged by the finger 51 secured to the movable leaf of the pneumatic 48, and a conduit 52 controlled by the spring-valve 50 and connected to the valve-
 10 action 31 which controls the pneumatic 28.

No claim is made in this application to the timed cut-out, just described.

For operating the reroll and tempo-indicator mechanism, a rod 53 is provided, connecting the lever 24 with a rock-shaft 54 which constitutes a part of suitable reversing and indicating mechanism. The reversing and indicating mechanism (not illustrated in its entirety, as it may be of any suitable type) controls the direction of rotation of the music-spool 55 and of the take-up roll 55^a. This take-up roll 55^a is provided with a hook 55^b for detachably engaging the ring 55^c of the music-sheet 78. To prevent accidental reversing of the travel of the music-sheet, a movable stop 56 is located in position to be engaged by the lever 24. This stop is mounted on a spring-support 57 (Fig. 7), and its movement is limited by means of a screw 58 embedded in the key-bed. The end of the stop 56 is provided with an abutment 59 for engaging the lever 24. The stop 56 is recessed at 60 to receive the lever 24 when the stop is moved down so that the abutment 59 clears the lever 24. For automatically moving the abutment 59 out of the way of the lever 24 at the end of the forward travel of the music-sheet, a pneumatic 61 is provided, having an arm 62 which extends within the recess 63 in the stop 56. This pneumatic 61 is connected by means of a conduit 64 with a valve-action 65, which valve-action also controls the pneumatic 66 which operates the reroll and action-cut-off mechanism. This pneumatic 66 is provided with a finger 67 on its movable leaf, which engages the down-turned end 68 of the action-cut-off rod 23, to which is secured the valve-rod 68^a of the action-cut-off valve. The pneumatic 66 is provided with a spring 69 for holding it in expanded position. The valve-action 65 is connected with the opening 70 in the tracker by means of the conduit 71. For stopping the music-spool 55 as soon as the music-sheet uncovers the opening 70, in rewinding, a pneumatic 72 is provided, having a hook-arm 73 secured to its movable leaf for engagement with the hook-arm 74 secured to rotate with the spindle 75 supporting the music-spool 55. The pneumatic 72 is connected, by means of the tube 76, with the valve-action 31 which controls the motor-stop-pneumatic 28.

65 The action of the parts thus far described

is as follows: To start the electric motor 17, the lever 24 is moved to the extreme right, causing the rod 23 to engage the rod 22 and close the switch 20. The lever 24 is then positioned to give the desired speed to the air-motor 12, or is manipulated to give any desired speed to the music-sheet. After the selection has been played, a perforation 77 in the music-sheet 78 registers with the opening 70 in the tracker, admitting air through the conduit 71 to the valve-action 65. This results in the collapse of the pneumatics 61 and 66. The pneumatic 61 will act under lower tension and therefore acts before the pneumatic 66. As the pneumatic 61 collapses, it moves the abutment 59 out of the path of the lever 24. As the pneumatic 66 collapses, the finger 67 engages the down-turned end 68 of the rod 23 and moves the lever 24 over until it enters the recess 60 in the stop 56. The movement of the lever 24 to this position will reverse the connections between the air-motor 12 and the music-spool 55 and take-up roll 55^a to cause the music-sheet to be rewound. At the same time, the rod 23 cuts off pneumatic communication of the player-action with the wind-chest 86 by movement of the valve-rod 68^a to close the attached action-cut-off valve. The complete, or nearly complete, rewinding of the music-sheet exposes the opening 32 in the tracker, and air is thus admitted, through the conduit 34, to the valve-action 31, causing the pneumatics 28 and 72 to collapse, opening the switch 20 to stop the motor 17 and throwing the hook-arm 73 into the path of the hook-arm 74 to stop the music-spool 55 from rotating, thus preventing the free end of the music-sheet 78 from flapping.

In order to effect the shutting off of the electric current and the stopping of the motor 17, should the lever 24 be left for a considerable length of time in zero position, the timed cut-out for the motor 17 is provided, as described above. The action of the timed cut-out is, briefly, as follows: If the lever 24 is moved to a position in which it engages the abutment 59, the tempo-indicator will be in zero position and pneumatic communication of the air-motor 12 with the wind-chest will be completely cut off, so that the air-motor will stop. When the lever 24 engages the abutment 59, the down-turned portion 42 of the rod 41 engages the push-button 43, causing the rod 44 to open the valve 45. Opening of the valve 45 admits air, through the conduit 46, to the valve-action 47, causing the pneumatic 48 to slowly collapse. When the pneumatic 48 is nearly collapsed, the finger 51 engages the spring-valve 50 and opens it, admitting air to the conduit 52, thus causing the operation of the valve-action 31, the collapse of the pneumatic 28, and the opening of the switch 20 whenever the lever 24 is allowed to remain

in the just-described position long enough for the slow-acting pneumatic 48 to reach and open the spring-valve 50.

- For controlling the speed of the air-motor 12, the down-turned portion 42 of the rod 41 is connected to the valve rod or stem 79 which is connected to the tempo-valve 80 (Fig. 4). The tempo-valve 80 controls the port 81 which affords communication between the air-motor 12 and the regulated-air passage 82 of the wind-chest 86, the air-pressure in the passage 82 being controlled by means of the regulator 83, which may be of any usual or suitable construction.
- For obtaining high speed of the air-motor 12, a high-tensioned valve 84 is provided, controlling the port 85 which affords direct communication between the air-motor and the wind-chest 86. This high-tension valve 84 is located in position to be opened by the tempo-valve 80, the extension 86 (Fig. 4) on the high-tension valve being engaged and lifted by the right-hand end of the tempo-valve as the latter is moved to the extreme right. In order to prevent injuriously high tension in the air-motor 12, a relief-valve 87 is provided, which controls an atmospheric port 87^a. This relief-valve 87 is mounted on a spring-support 88 fulcrumed about a screw 89. The tension of the spring-support 88 is regulated by means of a screw 90. The regulator 83 acts to govern the air-tension to the air-motor 12 during the winding operation of the music-sheet winding and rewinding gearing. The relief-valve 87 acts as a means to limit the air service to the air-motor during the rewinding operation. The regulator 83 and the relief-valve 87 act alternatively relatively to each other.
- The air-motor 12 is in communication with the valve-box 90^a through the conduit 91, which constitutes the air service connection from the regulator 83 and relief-valve 87 to the air-motor 12. The wind-chest 86 is in communication with the air-pump 16 through the conduit 92, past the check-valve 93, through the conduit 94, junction-block 95, conduit 96, junction-block 37, and conduits 38 and 39.
- The operation of the parts just described is as follows: The tempo-valve 80 can be placed in any desired position, with respect to the port 81, to give any desired speed to the air-motor 12, by means of the lever 24. When the lever 24 is moved to "rewind" position, i. e., the position which reverses the connections to cause rewind of the music-sheet, the tempo-valve 80 engages the high-tension valve 84 and opens the port 85, thus connecting the air-motor directly with the wind-chest 86. If the tension in the wind-chest 86 becomes excessive, the relief-valve 87 will open, against the pressure of the spring-support 88, to relieve the tension and prevent undue strain upon the air-motor.

This relief-valve 87 is particularly useful when the air-motor 12 is suddenly stopped, due to the hook-arm 74 engaging the hook-arm 73.

The expression-mechanism 13, for controlling and graduating the volume of tone by causing various degrees of air-tension to apply in the action wind-chest through variations in the admission of atmospheric air, may be the same as that described in my aforesaid earlier application, Serial No. 97,153, filed May 12, 1916, of which this application is a division.

As described in said application, Serial No. 97,153, the construction of the expression-mechanism 13 is such that, when a perforation in the music-sheet 78 registers with the tracker-opening 97 (Fig. 11), it will cause the application of high tension in the wind-chest. In order to cause positive actuation of the reroll pneumatics 61 and 66, the music-sheet 78 is provided with a perforation 98, which will register with the tracker-opening 97 when the perforation 77 registers with the reroll opening 70 in the tracker. This causes the application of high tension in the wind-chest when the reroll pneumatics 61 and 66 are actuated, thus causing these pneumatics to act promptly and reliably. It will be noted that there are no perforations in the music-sheet for registration with the motor-stop opening 32 in the tracker, as this opening 32 is flushed only when the music-sheet leaves the tracker, as, for instance, when the music-sheet has been completely rewound. As a consequence of the fact that the music-sheet has no perforation for registration with the opening 32, there are no perforations in the music-sheet which will travel anywhere near the reroll opening 70 in the tracker, so that there is no danger of accidental actuation of the reroll mechanism.

What I do claim as my invention, and desire to secure by Letters Patent, is:

1. A pneumatic sheet-controlled musical instrument comprising a device for inducing air-tension, a motor for operating said device, and a hand-operated device for controlling the traveling speed of the music-sheet and for controlling said motor.

2. A pneumatic sheet-controlled musical instrument comprising a device for inducing air-tension, a motor for operating said device, and a hand-operated device for controlling the traveling speed of the music-sheet and for starting said motor.

3. A pneumatic sheet-controlled musical instrument comprising a device for inducing air-tension, a motor for operating said device and a hand-operated device movable between two positions to control the traveling speed of the music-sheet and movable beyond one of said positions to control said motor.

4. An automatic sheet-controlled musical instrument comprising a manually controlled device movable between two positions to control the traveling speed of the music-sheet 5 and movable beyond one of said positions to reverse the travel of the music-sheet, and sheet-controlled means acting on said manually controlled device to effect the reversal of the travel of the music-sheet.
- 10 5. An automatic sheet-controlled musical instrument comprising a manually controlled device movable between two positions to control the traveling speed of the music-sheet, a stop movable into and out of the 15 path of movement of said device for stopping said device in one of said positions, said device being movable beyond said one of said positions to reverse the travel of the music-sheet, and sheet-controlled means for controlling said stop.
- 20 6. An automatic sheet-controlled musical instrument comprising a manually controlled device movable between two positions to control the traveling speed of the music- 25 sheet, a stop movable into and out of the path of movement of said device for stopping said device in one of said positions, said device being movable beyond said one of said positions to reverse the travel of the 30 music-sheet, sheet-controlled means for moving said stop out of the path of movement of said device, and means for moving said device beyond said one of said positions to effect the reversal of the travel of the music- 35 sheet.
7. The combination, with a music-sheet having a re-roll perforation and a high-tension perforation, of an automatic musical instrument having a tracker over which said 40 music-sheet passes, means for reversing the travel of said music-sheet, a pneumatic for controlling said reversing means controlled by said re-roll perforation, and an air-tension device controlling the degree of air-tension 45 for actuating said pneumatic, and controlled by said high-tension perforation, whereby when said high-tension perforation crosses said tracker, a comparatively high degree of air-tension will be caused for 50 actuating said pneumatic.
8. An automatic sheet-controlled musical instrument comprising an air-pump, an electric motor for operating said air-pump, manually controlled means for starting said 55 motor and sheet-controlled means for stopping said motor, comprising a switch and a pneumatic for actuating said switch, said manually controlled means being inoperative to stop said motor.
- 60 9. An automatic sheet-controlled musical instrument comprising a tracker; means for causing the music-sheet to travel forwardly over said tracker, comprising a take-up roll; means for rewinding the music-sheet on the 65 music-spool, said take-up roll being provided with means for securing a music-sheet thereto in such a manner that it will be released therefrom when it has been rewound; and sheet-controlled means for opposing the action of said rewinding means when the music-sheet has uncovered a certain opening in said tracker.
10. An automatic sheet-controlled musical instrument comprising a tracker; means for causing the music-sheet to travel forwardly 70 over said tracker, comprising a take-up roll; means for rewinding the music-sheet on the music-spool, said take-up roll being provided with means for securing a music-sheet thereto in such a manner that it will be released therefrom when it has been rewound; sheet-controlled means for opposing the action of said rewinding means when the music-sheet has uncovered a certain opening in said tracker; an air-pump; a motor for operating said air-pump; and sheet-controlled means for stopping said motor when the music-sheet has uncovered a certain opening in said tracker.
11. An automatic sheet-controlled musical instrument comprising an air-motor for causing the travel of the music-sheet, an air-pump, means affording communication between said air-motor and said air-pump, an atmospheric port leading to said communication means, and a yielding pressure-operated valve controlling said port.
12. An automatic sheet-controlled musical instrument comprising a tracker; means for causing the music-sheet to travel forwardly 90 over said tracker, comprising a take-up roll; means for rewinding the music-sheet on the music-spool, said take-up roll being provided with means for securing a music-sheet thereto in such a manner that it will be released therefrom when it has been rewound; and sheet-controlled means for stopping said rewinding means, comprising a rotatable member actuated by said rewinding means and a member movable into and 95 out of the path of said rotatable member.
13. An automatic sheet-controlled musical instrument comprising a tracker; means for causing the music-sheet to travel forwardly over said tracker, comprising a take-up roll; means for rewinding the music-sheet on the music-spool, said take-up roll being provided with means for securing a music-sheet thereto in such a manner that it will be released therefrom when it has been rewound; and sheet-controlled means for stopping said rewinding means, comprising a rotatable member actuated by said rewinding means, a sheet-controlled pneumatic, and a member movable by said pneumatic into and out of the path of said rotatable member.
14. An automatic sheet-controlled musical instrument comprising a tracker; means for causing the music-sheet to travel forwardly 110

over said tracker, comprising a take-up roll; means for rewinding the music-sheet on the music-spool, said take-up roll being provided with means for securing a music-sheet thereto in such a manner that it will be released therefrom when it has been rewound; and sheet-controlled means for obstructing the action of said rewinding means when the music-sheet has uncovered a certain opening in said tracker.

15. A music-sheet winding-and-rewinding apparatus, shifting-means for reversing said apparatus from winding to rewinding and from rewinding to winding, and to a neutral intermediate position, and a stop positioned to determine the said neutral position of said shifting-means.

16. A music-sheet winding-and-rewinding apparatus, shifting-means for reversing said apparatus from winding to rewinding and from rewinding to winding, and to a neutral intermediate position, and a stop positioned to determine the said neutral position of said shifting-means, said stop adapted to be thrown in and out of co-operation with said shifting-means.

17. A music-sheet winding-and-rewinding apparatus, mechanical shifting-means for reversing said apparatus from winding to rewinding and from rewinding to winding, and to a neutral intermediate position, pneumatic-means adapted to operate the said mechanical shifting-means, and a mechanical stop positioned to terminate the movement of the said mechanical shifting-means at the said neutral position.

18. A music-sheet winding-and-rewinding apparatus, mechanical shifting-means for reversing said apparatus from winding to rewinding and from rewinding to winding, and to a neutral intermediate position, pneumatic-means adapted to operate the said mechanical shifting-means, and a mechanical stop positioned to terminate the movement of the said mechanical shifting-means at the said neutral position, said stop adapted to be thrown in and out of co-operation with said mechanical shifting-means.

19. A music-sheet winding-and-rewinding apparatus, mechanical shifting-means for reversing said apparatus from winding to rewinding and from rewinding to winding, and to a neutral intermediate position, pneumatic-means adapted to operate the said mechanical shifting-means, a mechanical stop positioned to terminate the movement of the said mechanical shifting-means at the said neutral position, a tracker having apertures therein, and connections from said apertures to said pneumatic-means.

20. A music-sheet winding-and-rewinding apparatus, auto-pneumatic shifting-means for shifting said apparatus from winding to rewinding, and control-means to effect high air-tension, said control-means correlated

with said shifting-means and adapted to bring into action such high air-tension during said shifting to rewinding, and to cause said high air-tension to cease when the movement of said shifting-means is completed.

21. A music-sheet winding-and-rewinding apparatus, shifting-means for reversing said apparatus from winding to rewinding and from rewinding to winding, and to a neutral intermediate position thereof, an electric cut-out and connections therefrom to said shifting-means, said cut-out adapted to be open against electric current when said shifting-means is at its said neutral position.

22. A music-sheet winding-and-rewinding apparatus, shifting-means for reversing said apparatus from winding to rewinding and from rewinding to winding, and to a neutral intermediate position thereof, an electric cut-out and connections therefrom to said shifting-means, said cut-out adapted to be open against electric current when said shifting-means is at its said neutral position, and to be closed to electric current at both winding and rewinding control positions of said shifting-means.

23. A music-sheet winding-and-rewinding apparatus, shifting-means for reversing said apparatus from rewinding to winding condition, or to a neutral intermediate position, an electric cut-out and connections therefrom to said shifting-means, said cut-out adapted to be open against electric current when said shifting-means is at its said neutral position.

24. A music-sheet winding-and-rewinding apparatus, shifting-means for reversing said apparatus from rewinding to winding condition, or to a neutral intermediate position, an electric cut-out and connections therefrom to said shifting-means, said cut-out adapted to be open against electric current when said shifting-means is at its said neutral position, and to be closed to electric current when said shifting-means is effecting either said winding or rewinding conditions.

25. A pneumatic note-sheet-controlled musical instrument comprising an air-pump, an electric motor for operating said air-pump, manually operable means for reversing the direction of travel of the note-sheet, and means whereby said manually operable means may be used to start said motor.

26. A pneumatic note-sheet-controlled musical instrument comprising an air-pump, an electric motor for operating said air-pump, manually operable means for controlling the speed of the note-sheet, and means whereby said manually operable means may be used to start said motor.

27. A pneumatic note-sheet-controlled musical instrument comprising an air-pump, an electric motor for operating said air-pump, manually operable means for controlling the speed of the note-sheet and for reversing the

direction of travel of the note-sheet, and means whereby said manually operable means may be used to start said electric motor.

5. 28. The combination with a music-sheet winding and rewinding apparatus, of automatic means operating to oppose the rewinding movement of said apparatus when the music-sheet has been rewound without placing strain upon the music-sheet.

10 29. The combination with a music-sheet winding and rewinding apparatus, of sheet-controlled means operating to oppose the rewinding movement of said apparatus when the music-sheet has been rewound without placing strain upon the music-sheet.

15 30. The combination with a music-sheet winding and rewinding apparatus including an air-motor, an air-pump for creating air-tension for said air-motor, and an electric motor for driving said air-pump, of automatic means operating to simultaneously oppose the rewinding movement of said apparatus and stop said electric motor when the music-sheet has been rewound.

30 31. The combination with a music-sheet winding and rewinding apparatus including an air-motor, and an air-pump for creating air-tension for said air-motor, of automatic means operating to simultaneously oppose the rewinding movement of said apparatus and stop said air-pump when the music-sheet has been rewound.

35 32. An automatic sheet-controlled musical instrument comprising an air-motor for causing the travel of the music-sheet, means operating to suddenly oppose the action of said air-motor when the music-sheet has been rewound, an air-pump, means affording communication between said air-motor and said air-pump, an atmospheric port leading to said communication means, and a yielding pressure-operated valve controlling said port to prevent dangerously high tension in the air-motor when said opposing means are 40 operated.

45 In witness whereof, I have hereunto subscribed my name.

ALFRED SWENSEN.
